BURNER CONTROL APPARATUS

Richard L. Longini, Chicago, Ill., assignor, by
mesne assignments, to Wheelco Instruments
Company, Chicago, Ill., a corporation of Illi-
nois

Application August 13, 1941, Serial No. 406,628

1 Claim. (Cl. 158—28)

This invention relates to safety apparatus for preventing the operation of a burner when the flame supervisory apparatus is in unsafe condition.

In burner control apparatus provided with a control circuit and a flame switch for controlling the fuel supply in accordance with the presence or absence of flame, it is highly important, in event that the flame switch is in unsafe condition (e. g. when there exists a leakage, between electrode circuit and ground, of about the same resistive order as the flame, in which event the circuit would respond as if a flame were present and open the fuel supply), to prevent starting while such condition exists, even when an actual attempt is made to start the burner.

The primary object of this invention is accordingly to provide a means for preventing such starting in a burner control apparatus of the character referred to above when the flame switch is in unsafe condition.

Other and further objects of this invention will become more apparent hereinafter as the same becomes better understood from an examination of the specification and claim in conjunction with the accompanying drawing wherein is shown diagrammatically and schematically a burner control apparatus including safety means embodying this invention.

Referring to the drawing more particularly, reference character 1 designates a flame electrode of the same general type shown in patent to W. H. Gille, No. 2,231,420 of February 11, 1941, for Burner control system or as shown in the copending application of Theodore A. Cohen, Richard L. Longini and Hans J. Ostermann, Ser. No. 274,904, filed May 22, 1939, for Burner control apparatus. The electrode 1 is provided with a flame rod 2 for contacting a flame from a pilot gas burner 4 and a main gas burner 3. The electrode 1 is connected by a cable 19 to an input terminal 32 of a flame switch apparatus 20. This flame switch apparatus 20 corresponds to the electronic apparatus shown and described in the aforesaid copending application but may be any variety of flame switches well known in the art. Reference number 33 designates the other output terminal of the flame switch electronic apparatus 20 which is grounded so that the input circuit to said apparatus may be completed by the presence of a burner flame in either the pilot burner 4 or the main burner 3. The output of the flame switch apparatus 20 is connected to energize coil 21 of a relay mechanism 22. The relay 22 includes an armature, which carries movable contacts 24 and 55

21, and fixed contacts 23, 25, 26 and 28. The relay 22, through its contacts, is connected to an electrically operated gas valve 6 supplying burner 3 with fuel, to an ignition transformer 5 and an electrically operated valve 7 for the pilot burner 4, to a safety relay 12 and a push button switch 10 so that these valves and ignition transformer will be opened and turned on automatically when push button 10 is depressed and a flame is present thereafter at either burner. If the flame switch is in unsafe condition so as to cause the pulling up of relay 22, for any reason such, for example, as the existence of a leakage between the electrode circuit and ground of the resistive order of the flame, it would be most unsafe to start the burner because of open condition of valve 6. In order to prevent the burner from starting when such an unsafe condition of the flame switch exists, even though the push button is depressed in an attempt to start the burner, I provide the particular arrangement to be hereinafter described.

The safety relay 12 includes a coil 17, movable contacts 13 and 15 and fixed contacts 14 and 16.

The push button switch 10 is adapted to be manually operated to start the burner and includes contacts 30, 29 and 31 and a manually operable member 34 for connecting said contacts together when depressed. Contact 30 is connected to a lead 36 which is connected to contacts 24 and 26 of relay 22 and to contact 16 of relay 12. Contact 29 is connected to a lead 37 going to ignition transformer 5 and electrical valve 7 to side 18b of the line. Contact 31 goes to a lead 38 connecting to coil 17. The other side of coil 17 goes to side 18b of the power line.

An alarm bell 11 is adapted to be energized when the flame at the burner is extinguished and the relay 22 automatically opens.

Reference character 18 designates the electrical power line comprising the two sides thereof 18a and 18b and numbers 8 and 9 refer to the pilot and main burner fuel supply lines, respectively.

Ignition transformer 5 and electrically operated pilot valve 7 are connected in parallel from side 18b of the power line 18 to contact 29 of the push button 10. Contact 30 thereof is connected to contact 26 of relay 22. Since contact 27 of relay 22 is connected to side 18a of the power line, transformer 5 and valve 7 will be energized upon depressing the push button 10 but only if relay 22 is open at and before the time of starting because contacts 28 and 27 are only closed when

relay 22 is open. Contact 31 is connected through coil 17 of relay 12 to side 18b of the power supply and contact 30 being connected to side 18a through contacts 26 and 27 when the push button 10 is depressed, relay 12 will pull up and close but, likewise, only if relay 22 is open at and before time of starting.

The contacts 15 and 16 of relay 12 are in parallel with contacts 26 and 27 of relay 22 whereby, when relay 12 closes, the latter contacts may be broken, upon the subsequent pulling up of relay 12, and the ignition transformer 5 and pilot valve 7 will remain on, so long as the push button 10 is depressed.

The main burner electrically operated gas valve 6 is connected from side 18b of the power line through contacts 25 and 24 of relay 22 and thence through contacts 16 and 15 of relay 12 to side 18a of the power line. Thus the main gas valve 6 will not open unless relay 12 is closed and safe starting condition of the flame switch assured as a necessary prerequisite and, in addition, said gas valve will not open unless and until relay 22 is closed subsequent to closing of relay 12, by operation of the burner flame impinging upon rod 2. However the premature closing of relay 22 (due to unsafe condition of the flame switch 20), before closing of relay 12, would prevent any start whatever by preventing the subsequent closing of relay 12 to thereby prevent energizing transformer 5, pilot valve 7 and coil 17 of relay 12, all of which have to be energized for a start attempt through contacts 26 and 27 of relay 22.

In order to prevent relay 12 from dropping out after a safe start has been made upon subsequent closure of relay 22 due to presence of flame, and after the push button 10 has been released, said relay 12 is locked closed by virtue of another connection being provided for energizing coil 17 other than the connection through said push button which was previously described. This locking connection for energizing coil 17 is dependent upon both relays 12 and 22 being closed in proper sequence (relay 12 first) and consists of a conductor 35 connected from said coil, at the side thereof opposite to side 18b of the line supply, to side 18a of the line supply through contacts 13 and 14 of relay 12 and contacts 27 and 28 of relay 22.

A flame failure or ground out will act, as described in the aforesaid copending application, to cause relay 22 to drop open to shut off fuel supply to main burner and unlock relay 12.

The aforesaid locking of relay 12 after a safe start will not prevent said relay from dropping open to shut off the fuel supply to the main burner when relay 22 is automatically opened by the flame switch 20 on account of flame failure or ground out as described in the aforesaid copending application.

The opening of valve 6 allows fuel to main burner 3 which fires from pilot 4 whereupon transformer 5 and pilot valve 7 are deenergized by the release of push button 10. The main flame from burner 3 striking electrode 2 maintains the system.

The alarm 11 is connected across opposite sides of the power line 18 through contacts 23 and 24 and through contacts 26 and 27 so that when relay 22 is open the alarm will be sounded to indicate the absence of flame at the burner.

The pilot burner may take any of the usual forms and is here shown of a type such as disclosed in the copending application of Richard L.

Longini, Ser. No. 330,157, filed April 17, 1940, for Burner.

Operation

In the operation of the apparatus, push button 10 is depressed to energize transformer 5 and pilot electric valve 7, through contacts 29 and 30 of the push button and through contacts 26 and 27 of relay 22, from the line 18. At the same time relay coil 17 of relay 12 is energized through push button contact 31 to close said relay. A flame appears at pilot burner 4 which contacts rod 2 whereupon the flame switch 20 pulls up its relay 22 to make contacts 24 and 25 and contacts 27 and 28 and to break contacts 23 and 24 and contacts 26 and 27. The making of contacts 27 and 28 allows the relay 12 to lock itself in closed position through the path of coil 17, contacts 13 and 14 and contacts 27 and 28 to line supply. Although contacts 26 and 27 are broken, upon pulling up of relay 22, the ignition transformer 5 and pilot valve 7 remain on by virtue of contacts 15 and 16 in relay 12 as long as the push button is depressed. The making of contacts 24 and 25, upon closing of relay 22, energizes the main gas valve through closed contacts 15 and 16 of relay 12. The opening of valve 6 allows fuel to flow to main burner 3 which is ignited by the flame at pilot burner 4. Upon releasing the push button 10, ignition transformer 5 and pilot electric valve 7 are deenergized whereupon the pilot flame at burner 4 is extinguished leaving the system maintained by the flame from main burner 3 impinging upon the flame rod 2. Should a flame failure occur, or should the system be grounded out, as described in the first of the aforementioned copending applications, the relay 22 is deenergized to break contacts 24 and 25 and to break contacts 28 and 27. At the same time contacts 23 and 24 and contacts 26 and 27 are made. The breaking of contacts 27 and 28 of relay 22, as well as the breaking of contacts 24 and 25, deenergizes main fuel supply valve 6 which stops fuel supply to main burner 3.

The making of contacts 23 and 24 and the making of contacts 26 and 27 energizes alarm 11 to indicate, audibly, that there has been a flame failure, or ground out.

The above describes normal functioning of the system as regards flame failure or grounding out of the flame rod 2.

When there is a leakage between flame rod 2 and the ground of substantially the same resistive order as that of the flame, apparatus heretofore used would be unsafe, inasmuch as valves such as 6 would be held open even when flame were absent. In this apparatus, when such leakage exists between flame rod 2 and ground, or from the electrode circuit to ground, the flame switch relay 22 will be held in closed position so that contacts 23 and 24 and contacts 26 and 27 are broken while contacts 24 and 25 and contacts 27 and 28 are made. Under these conditions, depressing push button 10, in an attempt to start the system, can perform no operation because, the contacts 26 and 27 being broken, the coil 17 of relay 12 cannot be energized nor can the ignition transformer 5 or the pilot electric valve 7 be energized. The breaking of contacts 26 and 27, in preventing energization of coil 17 or resultant closing of relay 12 and the latter's contacts 15 and 16, thus prevents energizing of the main fuel valve 6.

Thus, in summary, if the safety relay 12 is not energized upon a starting attempt being made,

due to previous leakage in the flame switch system, the main fuel supply is not available.

It is obvious that the safety mechanism 12 can be added to any variety of manually or semi-automatically started flame supervisory systems to insure safe operation in event of any leakage which in effect would maintain the flame switch closed during flame absence or ground out.

The aforescribed system is set in operation or removed from operation, as required, by a switch 40 which may be manual or may be automatic in the form of a pressurestat or a thermostat, e. g. like the switches 68 or 69 in the aforesaid co-pending application, in response to a call for heat. Obviously opening of switch 40, when heat is no longer desired, will cause the system, including fuel supply valve 6, to shut down.

I am aware that many changes may be made and details varied without departing from the principles of my invention and I therefore do not wish to be limited to the details shown or described.

I claim:

The combination of a burner, a flame switch mechanism operable by an electric circuit responsive to and capable of being completed through a burner flame, or through a corresponding leak-

age path having a like resistance, said mechanism including a relay adapted to be energized when said circuit is completed, switch means operable by said relay to close when the relay is de-energized, and to open when the relay is energized, a second relay having an operating coil and switch means adapted to be closed when said coil is energized, ignition means for the burner, a starting switch, an electric burner fuel supply valve, a source of electrical energy, connections for energizing said coil from said source through said starting switch and said first switch means, only when the latter is closed, and thereafter, upon closure of the second switch means, to energize said coil through said second switch means in lieu of through the starting switch (but still through the first switch means), connections for energizing said ignition from said source when the starting switch is closed and the first switch means is closed, supplemental switch means operable by the first mentioned relay to close when said first relay is energized and connections for energizing said fuel supply valve through said last mentioned switch means and the second mentioned switch means only when both are closed.

RICHARD L. LONGINI.
